HERBERT H. PATTEE, OF NEW YORK, N. Y.

DESIGN FOR A BODY OF CARS OR FLOATS.

No. 38,171.

Specification for Design.

Patented Aug. 14, 1906.

Application filed April 10, 1906. Serial No. 310,988. Term of patent 7 years.

To all whom it may concern:

Be it known that I, HERBERT H. PATTEE, a citizen of the United States, residing at New York, county of New York, State of New York, (whose post-office address is 69 West Thirty-eighth street, New York city,) have invented a new, original, and ornamental Design for Bodies of Floats or Cars, of which the following is a specification, reference being had to the accompanying drawings, forming a part thereof, and in which—

Figure 1 is a side elevation of the body of a car or float. Fig. 2 is a front view. Fig. 3 is a rear view of the same.

I claim—

The ornamental design for the body of a car or float, as shown.

HERBERT H. PATTEE.
